UNITED STATES PATENT OFFICE

JOHN F. HUNTER, OF ST. LOUIS, MISSOURI

COMPARTMENT CLOSET

Application filed May 5, 1928. Serial No. 275,427.

This invention relates to a compartment closet and it is an object of the invention to provide a device of this kind adapted to be arranged upon the back or inside of a closet door or the like.

Another object of the invention is to provide a closet of this kind comprising a plurality of hingedly connected casings each constituting a compartment and assembled in a manner whereby selective access may be had when desired within any one of said casings or compartments.

Furthermore, it is an object of the invention to provide a device of this kind comprising a plurality of casings which, when in closed position, are in overlying relation together with means for maintaining the same in such position, said casings being mounted in a manner to permit them to have relative movement for access to the interior of any particular one.

The invention consists in the details of construction and in the combination and arrangement of the several parts of my improved compartment closet whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in elevation of a door in closed position with an applied compartment closet indicated by broken lines;

Figure 2 is a view similar to Figure 1 with the door in open position and the applied compartment closet in elevation;

Figure 3 is a view in elevation of the compartment closet as herein disclosed with one of the casings in open position;

Figure 4 is a fragmentary vertical sectional view taken substantially on the line 4—4 of Figure 2;

Figure 5 is a sectional view taken substantially on the line 5—5 of Figure 1 with

a second position of the door and compartment closet carried thereby indicated by broken lines;

Figure 6 is a sectional view taken substantially on the line 6—6 of Figure 3;

Figure 7 is a vertical sectional view taken substantially on the line 7—7 of Figure 5;

Figure 8 is an enlarged fragmentary horizontal sectional view taken substantially on the line 8—8 of Figure 1.

As disclosed in the accompanying drawings, D denotes a door of a conventional type herein disclosed as coacting with a closet C and which has one vertical marginal portion hingedly connected, as at 1, 65 for swinging movement in a horizontal direction into either open or closed position.

My improved compartment closet comprises a plurality of casings M which, when in relatively closed position, are in overlying relation as particularly illustrated in Figure 5 with adjacent side walls 2 of the casings flush. Each of these casings M has its inner face open but closed by the outer or rear wall 3 of an adjacent casing M when in closed position. The casings M in succession are of increased width with the widest casing having its side wall 2 in direct hinged connection, as at 4, with the rear or back face of the door D closely adjacent to its hinged vertical margin. By having the casings M in succession of different widths, the door D and the applied compartment closet may be readily swung into open or closed position without hindrance or obstruction as is clearly indicated in Figure 5 of the accompanying drawings.

The outer side wall 5 of each of the casings M together with the back wall 3 of an adjacent casing M and also the back or rear wall of the door D are provided, as at 6, with coacting means whereby the casings M may be effectively locked in closed position yet permitting any one of said casings M to be released when it is desired to have access thereto.

My improved compartment closet permits the effective hanging or storage of garments in a manner whereby they will be fully protected and which permits access to the garment or garments within one of the casings 100

without in any way interfering with the garments in the remainder of the casings.

From the foregoing description it is thought to be obvious that a compartment closet constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A compartment closet structure, comprising a door designed to be hingedly mounted to close an opening, a plurality of casings hingedly connected together at one side and each having one side open, each casing but one having its open side normally closed by an adjacent casing, the excepted casing being hingedly attached to and supported by said door and having its open side normally closed thereby, said casings being detachably connected together and adapted to move as a unit with the door.

2. A compartment closet structure, comprising a door designed to be hingedly mounted at one side of and to close a door opening, a plurality of relatively flat casings of graduated widths arranged in tandem with their side faces at one side of the structure, in alignment, hinged connections between said casings, said casings each having one face open and all except one being normally closed by the back of an adjacent casing, and a hinged connection between the excepted casing and said door, said excepted casing having its open face normally closed by the door, the tandem arrangement of said graduated casings permitting all of the casings to swing through the door opening as a unit upon the door body.

In testimony whereof I hereunto affix my signature:

JOHN F. HUNTER.
